UNITED STATES PATENT OFFICE.

JOHN KIEWICZ, OF HYDE PARK, MASSACHUSETTS.

SEWING-MACHINE.

1,014,231.

Specification of Letters Patent.

Patented Jan. 9, 1912.

Application filed January 20, 1911. Serial No. 603,656.

To all whom it may concern:

Be it known that I, JOHN KIEWICZ, a citizen of the United States, and resident of Hyde Park, county of Norfolk, State of Massachusetts, have invented an Improvement in Sewing-Machines, of which the following description, in connection with the accompanying drawing, is a specification, like characters on the drawing representing

10 like parts.

This invention has for its object the production of a sewing machine particularly adapted for attaching a rib or strip, such as a cord, to one face of a fabric by a series 15 of stitches coöperating with and penetrating the cord and the fabric, respectively, but which are invisible at the face of the fabric farthest from the cord.

One of the special purposes for which 20 this invention is designed is the manufacture of inner soles for welted boots and shoes, the inner sole being made of thin stock and having attached to one face thereof a rib, strip or cord extending from the 25 shank portion near one edge around the fore part of the inner sole and back to the shank portion near the opposite edge thereof. In the manufacture of the boot or shoe such rib, cord or strip, (the terms 30 being herein used synonymously,) is utilized for connecting the inner sole, upper, and welt, in a well known manner, and it takes the place of a lip or feather formerly used and which required the inner sole to be 35 made of relatively thick and expensive stock.

More recently inner soles have been made in large numbers of two superposed plies of canvas or similar fabric cemented together, and with an interposed rib or cord carried around the forepart from the shank, one of the plies of fabric being molded closely about the rib or cord. For some 40 classes of work inner soles of this character 45 are objectionable and there is a great demand for a cheap and serviceable inner sole which can be made of thin leather stock or the like with a welt-attaching rib or cord, and such an inner sole can be produced rapidly and cheaply by the sewing machine embodying my present invention.

Inasmuch as stitching on the face of an inner sole is objectionable I have so constructed and arranged my sewing machine 50 that the fabric is bent before it is pene-

trated by the needle so that the latter may enter and its point emerge from the same side or face of the fabric to produce a blind stitch, the needle on alternate thrusts penetrating and passing through the cord, of 60 any suitable character, the concatenation of the two sets of stitches securely uniting the fabric and the cord in a neat and durable manner.

The various novel features of my invention will be fully described in the subjoined specification and particularly pointed out in the following claims.

Figure 1 is a top plan view of a sufficient portion of a sewing machine to be understood, embodying one form of my present invention, the overhanging arm and its adjuncts being omitted, a part of the bed-plate also being omitted to show portions of the mechanism which would otherwise be hidden; Fig. 2 is a front elevation of the apparatus illustrated in Fig. 1, with a part broken away on the line 2, Fig. 1, a portion of the overhanging arm, the presser-foot, bender and bender-bar, and the work 70 or stock and the adjacent cord are also shown; Fig. 3 is a side elevation of the cam for controlling the movement of the feed-block; Fig. 4 is an enlarged sectional detail taken on the line 4—4, Fig. 1, looking toward the left, but with the feed-block in elevation, the work or stock being shown in section and the cord in elevation, the various parts being shown just as the bender 75 is about to descend; Fig. 5 is a view similar to Fig. 4 of the feed-block and adjacent parts, but with the same position for the needle to penetrate the cord on its next forward stroke or thrust; Fig. 6 is a transverse sectional detail on the line 6—6, Fig. 95 5, with the cord crossing the path of the needle; Fig. 7 is a similar sectional view but showing the bend formed in the work in readiness to be penetrated by the needle, the cord being positioned below the needle 100 path; Fig. 8 is an underside view of an inner sole having a cord attached thereto by the sewing machine embodied herein.

For convenience hereinafter I shall designate the stock or fabric in which the blind stitches are taken as the work, indicated at w^* , and the rib or strip to be attached thereto as the cord, indicated at c^* , and in practice it will usually be a series 105 of strands of yarn or thread twisted to- 110

gether to form a strong cord, but it is to be understood that my invention is not restricted to an attached member of that particular character or material.

5 In the construction of the sewing machine in accordance with my present invention I have utilized a portion of the apparatus shown and described in United States Patent No. 404,863 granted June 11, 10 1889 to John Reece for finishing button-hole pieces, but material changes have been made in certain important features to be pointed out hereinafter.

The bed-plate A, the overhanging arm 15 A' (partly shown in Fig. 2) the vertically reciprocating bender-bar A⁸ actuated by the link A⁴ through a vibrating lever mounted on the arm A' and not shown herein, the presser-foot B' and its bar B; the 20 rotating main shaft A² and its attached cam disk b²; the eye-pointed needle a⁶ secured to the needle-bar a⁷ reciprocated in bearings a⁸ in a yoke-like frame A¹⁸; and the link b connected at one end by a stud 25 2 with a collar on the needle-bar and at its other end pivoted on a crank-pin b' on the disk b², to reciprocate the needle-bar, may be and are all substantially as in the said patent to Reece, except that herein 30 the frame A¹⁸ is held fixedly on the main frame or bed A^x of the machine by screws 3, for in my present invention the needle-bar has no lateral vibration but is reciprocated in a single, fixed path below the bed-plate. As will be pointed out later the 35 bender is actuated from a second rotating shaft, in the present invention, instead of from the shaft A², as in the Reece patent.

The needle-guide b³, fulcrumed at b⁴ is 40 raised and lowered by the cam-shaped periphery of the disk b², which acts upon the spring finger 5 attached to the arm 8 extended at one end under the needle-guide and at its other end secured by a screw 9 45 to a stand 10 of the main frame, see Fig. 1, all substantially as in the Reece patent, the upturned end of the needle-guide rising and falling in an opening in the throat-plate, as will be pointed out hereinafter. In said 50 patent the part of the guide which co-operates with the needle is shown as beveled, while herein said part is shown as slightly grooved or notched, but the function of said guide is the same, namely, to steady 55 the needle on its forward thrust as it is about to penetrate the material.

It will be manifest that the needle a⁶ makes a complete reciprocation for every revolution of the shaft A², and as herein 60 the work is bent, and penetrated by the needle, only on each alternate forward thrust of the needle the bender is actuated from a second shaft 20, having an attached gear 21 meshing with and driven by a gear 65 22 on the shaft A², the relative diameters

of the gears being such that shaft A² revolves twice for each revolution of the shaft 20.

The lower end of the link A⁴ is forked at 23 to embrace shaft 20 and has a roll 24, 70 see dotted lines Figs. 2 and 4, which travels in the groove 25 of a cam disk 26 fast on shaft 20, whereby the bender-bar A⁸ is depressed and elevated at every revolution of shaft 20, and as shown in Fig. 2 the cam-groove is just about to coöperate with roll 24 to effect the descent of the bender-bar and its attached bender 27. The lower end of said bender is flattened and reciprocates in a plane at right angles to the needle path, and as shown in Fig. 7 the lower end of the bender clears the needle when it forms a bend in the work w^x so that on its forward thrust the needle can penetrate the bend, as is usual in sewing machines of 80 this general type. When the bender descends it passes through the slotted presser-foot B', resting upon the work, and bends the work in a grooved throat-plate, to be described, the bend lying in the direction of the feed. A throat-plate 28 is let into a suitable recess in the bed-plate A, said throat-plate having quite a deep longitudinal cord-guiding groove 29 formed therein, the bottom of said groove being below the surface of the bed-plate, see Figs. 4 and 5, and it is slotted longitudinally at 30 below the bender, an offset part 31 of the slot, Fig. 1, permitting the upturned part of the needle-guide b³ to rise and fall 100 therein.

As shown in Figs. 6 and 7 the side walls of the cord-guiding groove 29 are oppositely apertured at 29^x for the passage of the needle across the groove near the upper 105 part thereof, said groove receiving and guiding the cord c^x beneath the work w^x, and the latter is bent into the groove by the descent of the bender, as will be readily understood.

A toothed feed-block 32, secured to or forming a part of a feed-bar 33, enters the slot 30 of the grooved throat-plate directly beneath the needle path, and said feed-block is moved longitudinally and vertically in the slot by 110 means to be described, the toothed face of the block being longitudinally grooved or concaved at 34, Figs. 6 and 7, to provide a seat for and to position the cord just beneath the needle during a part of the cycle 115 of the machine. The feed is from left to right, viewing Figs. 4 and 5, and the left hand end of the feed-bar is mounted to slide and rock in a seat 35 in the bed A^x of the machine, an adjustable stop 36 being arranged to coöperate with a lug 37 on the feed-bar to determine the starting point of the feed-stroke. The inner end of the feed-bar is connected with the free end of a spring arm or retractor 38 attached at 39 to the 120 125 130

under side of the bed-plate and depending therefrom, said spring arm normally tending to retract the feed-bar to the position shown in Fig. 5 and to depress its inner end, 5 as shown in Fig. 4, the retractive action of the spring arm effecting the return stroke of the feed-block to starting position and the depressing action serving to lower the feed-block from engagement with the cord. A 10 disk 40 fast on the shaft 20 has its periphery cam shaped, presenting a high part 41 and a low part 42, Fig. 3, and one side of said disk is provided with a segmental cam lump or projection 43, this cam disk coöperating 15 with a lever 44 having a horizontal fulcrum 45 on a block 46 pivoted to rock on a vertical pivot 47 depending from the bed-plate. The free end of the lever passes under the feed-bar 33 and rests in an elongated notch 20 48 in its lower edge, said lever having lips or shoulders 49, 50, Fig. 4, which coöperate respectively with the periphery of the cam disk 40 and the segmental projection 43 thereon. 25 When the feed-bar and its block 32 are in the position shown in Fig. 5 the high part 41 of the edge cam is acting upon the shoulder 49 to hold the free end of lever 44 elevated, and at such 30 time the feed-block is stationary and positively held in elevated position, beneath and at the minimum distance from the needle path, the toothed face of the feed-block being in engagement with the cord c^x , 35 the latter being thereby positioned in the needle path and supported directly thereunder, while the work w^x is substantially flat and held on the throat-plate 28 by the presser B'. The timing of the mechanism 40 is such that when the parts just referred to are positioned as in Figs. 5 and 6 the needle a^x is moved forward, penetrates the cord, and carries the needle-thread n through it, the loop of needle-thread being entered by 45 the shuttle-thread s , the shuttle C, indicated by dotted lines Fig. 1, being of any usual or suitable construction and being actuated by usual mechanism common to sewing machines of this type. When the needle is 50 thrust into the cord the latter tends to bend in front of the needle, and the latter tends to slip off the cord, but this tendency is overcome by the feed-block, for it not only vertically supports the cord but holds it 55 laterally against displacement by the side walls of the groove 34 in the feed block. The stitch having been formed in the cord c^x the needle is retracted, the feed-block supporting the cord directly beneath the needle 60 during the penetrating and retracting strokes thereof, and as the needle is withdrawn from the cord the side cam 43 acts on the shoulder 50 of lever 44 and swings the latter to the right viewing Fig. 5, so 65 that the feed-block 32, which is still elevated by the high part 41 of the edge cam, is moved to the right, and the teeth of said feed-block act upon the cord lying in the groove 34 and effect the feed of the cord and the work w^x to the right, flexing the spring 70 arm 38. As the feed-stroke is completed the low part 42 of the edge cam permits said spring arm 38 to depress the inner end of the feed-bar, lowering the feed-block away from the cord, see Fig. 4. Now the 75 bender 27 descends, by the mechanism previously described, and bends the work w^x into the groove 29, see Fig. 7, and the needle a^x makes its forward thrust, this time penetrating the bend in the work and carrying the loop of needle-thread through the bend to be entered by the shuttle-thread, to form the blind stitch in the work. During this 80 operation the side cam 43 has ceased to act on the shoulder 50 of lever 44, and the spring 85 arm 38 acts to swing said lever to the left, Figs. 4 and 5, about the vertical pivot 47, and thereby the feed-bar and feed-block will be moved to the left, as far as permitted by the adjustable stop 36. As the needle is 90 withdrawn from the bend the part 41 of the edge cam again coöperates with the shoulder 49, swings up the lever 44 on its horizontal fulcrum 45 and the feed-block 32 is positively lifted into engagement with the cord 95 c^x , elevating the latter and the work w^x until the cord is again vertically and laterally positioned and upheld in the path of the needle, to be penetrated thereby on the next forward thrust of the needle, completing 100 the cycle, for the feed-block is now in position at the starting end of the feed stroke. Thus on one forward stroke the needle penetrates the cord, which is fixedly held in position by the positively elevated feed-block 105 and the presser-foot B' resting upon the work w^x , the feed-block affording a firm support for the cord directly beneath the needle as the latter penetrates the cord, and this 110 fixed position and firm, positive support of the cord is maintained until the needle has passed through the cord and been withdrawn therefrom, forming a stitch in the cord, and thereafter, but before the bend is formed in the work w^x the feed takes place, 115 effected by the coöperation of the feed-block with the cord and on the next forward stroke of the needle the bend in the work is positioned for penetration by the needle, for the formation of the blind stitch in the work. 120 By the described cycle of operation the cord is securely attached to the work, the stitching being invisible at the face of the work farthest from the cord, and the stitching connecting said cord with the work is 125 drawn around the portion of the cord nearest the work, and practically invisible when the stitches are drawn taut by usual take-up devices forming no part of this invention. The position of the feed-block directly be- 130

neath the needle path provides for direct support and positive control of the cord when the needle coöperates therewith, at a point immediately adjacent the needle.

5 Inasmuch as alternate stitches are formed in the work and the intervening stitches are formed in the cord the latter is very firmly and securely attached to the work, so that the machine shown and described herein is particularly adapted for making corded innersoles such as hereinbefore referred to and illustrated in Fig. 8. It is important that the cord be held firmly in position, both laterally and vertically for penetration by the needle on alternate forward thrusts of the latter, particularly if the cord be hard twisted or presents considerable resistance to penetration by the needle, and it will be seen that the gripping or clamping action at this time effected by the elevated and stationary feed-block upholding the cord directly beneath the needle, and the coöperation of the presser-foot is positive and exact, permitting no movement of the cord during the coöperation of the needle therewith.

20 25 The groove 29 in the throat-plate guides the cord both in its longitudinal movement when the feed takes place and vertically when the feed-block rises and falls.

30 35 Changes or modifications in details of construction and arrangement may be made by those skilled in the art without departing from the spirit and scope of my invention as set forth in the claims annexed hereto.

35 Having fully described my invention, what I claim as new and desire to secure by Letters Patent is:

1. In a sewing machine, a throat plate having a slotted cord guiding groove, a stitching mechanism including a needle, and means to reciprocate it in a path transversely of the groove, a vibrating bender to intermittently engage and bend the work into the slotted portion of the groove, a cord positioning feed block having a concaved cord engaging surface and cord engaging teeth and located directly beneath the needle path and movable in the slotted portion of the groove, and means to operate said feed block to position the cord in the path of the needle.

40 45 50 55 60 65 65

2. In a sewing machine, a throat-plate having a slotted cord-guiding groove, a stitching mechanism including a needle, and means to reciprocate it in a path transversely of the groove, a vibrating bender to intermittently engage and bend the work into the slotted portion of the groove, a cord positioning feed-block having a concaved cord-engaging surface and cord-engaging teeth and located directly beneath the needle path and movable in the slotted portion of the groove, means to elevate said feed-block toward the needle path thereby

70 75 80 85 90 95 100 105 110 115 120 125 130

to place a cord sustained by the feed-block in position to be penetrated by the needle and to hold said feed-block stationary in its elevated position while said needle penetrates and is withdrawn from the portion of the cord immediately above and upheld by said feed-block and then to give said feed-block a forward feeding movement while in its elevated position with its teeth in engagement with the cord, the concaved cord-engaging surface acting to sustain the cord laterally against the thrust of the needle when said cord is upheld and penetrated by the needle, and means to depress the feed-block and return it to neutral position while the bender descends to form a bend in the work.

3. In a sewing-machine, a throat-plate having a cord-guiding groove longitudinally slotted in its bottom and at right angles to the needle path, a cord-positioning feed-block having a concaved operative face and vertically and longitudinally movable in the slotted part of the groove and having cord-engaging teeth, a vertically reciprocating bender to intermittently engage and bend the work into the slotted portion of the groove, stitch-forming mechanism, including an eye-pointed needle reciprocated in a fixed path above the feed-block, to penetrate, on successive forward thrusts, a bend in the work and a cord at the underside of the work positioned in the needle path by the feed-block, the cord when penetrated by the needle being upheld beneath the latter by the feed-block, and mechanism to effect the actuation of the feed-block, said mechanism comprising means to elevate the feed-block and then to maintain said feed-block at rest for a sufficient length of time to permit the needle to penetrate the cord and then withdraw therefrom, while the cord is upheld by the feed-block directly under the needle, and then to give said feed-block a forward movement to feed the cord.

4. In a sewing-machine, a throat-plate having a cord-guiding groove longitudinally slotted in its bottom and at right angles to the needle-path, a feed-block having a toothed face longitudinally grooved and vertically and longitudinally movable in the slotted part of the groove, a vertically reciprocating bender to intermittently engage and bend the work into the said groove, stitch-forming mechanism, including a horizontally-reciprocating eye-pointed needle to penetrate, on successive forward thrusts, a bend in the work and a cord at the under side of the work positioned in the needle path by the feed-block, the latter engaging and supporting the cord vertically and laterally when penetrated by the needle, and positively acting means to maintain the feed-block elevated and stationary during each cord-penetrating thrust of the needle

and to effect the feed-stroke of the block while elevated and with its toothed face in engagement with the cord after withdrawal of the needle from the cord and prior to 5 the next forward thrust of the needle into a bend in the work.

5. In a sewing-machine, a throat-plate having a cord-guiding groove longitudinally slotted in its bottom and at right angles to the needle path, a cord-positioning feed-block having a concaved operative face and vertically and longitudinally movable in the slotted part of the groove, a vertically reciprocating bender to intermittently engage and 10 bend the work into the slotted portion of the groove, stitch-forming mechanism, including an eye-pointed needle reciprocated in a fixed path to penetrate, on successive forward thrusts, a bend in the work and a 15 cord at the underside of the work positioned in the needle path by the feed-block, a longitudinally slideable and vertically swinging bar on which the feed-block is mounted, a cam coöperating with said bar to lift it 20 positively thereby to place a cord in said groove in position to be penetrated by the needle, said cam being provided with a dwell of considerable length which maintains the feed-block stationary in elevated position 25 during each cord-penetrating thrust and subsequent retraction of the needle, said cam having also a lateral portion which becomes active after the termination of the dwell to move said bar longitudinally to effect the 30 feed-stroke of the block while it is elevated and in engagement with the cord, and a single spring coöperating with the bar to depress it and the feed-block while the bender descends and to return said bar and 35 the feed-block to the starting end of its feed stroke while the needle is penetrating the bend in the work.

6. In a sewing-machine, a longitudinally slotted throat-plate having means to guide a cord at right angles to the needle-path, a vertically reciprocating bender to intermittently engage the work above the slotted portion of said throat-plate and bend the work thereat, stitch-forming mechanism, including a horizontally - reciprocating eye-pointed needle to penetrate the bends in the work on each alternate forward thrust, and to penetrate a cord held at the underside of the work on each intervening forward thrust 45 of the needle, a feed-block having cord-engaging teeth and movable longitudinally and vertically in the slotted portion of the throat-plate, the toothed face of the feed-block being also longitudinally concaved to 50 receive and uphold the cord and to support it laterally against the thrust of the needle, and means to maintain said feed-block elevated and stationary during the cord-penetrating thrust of the needle and to effect 55 the feed-stroke of said block prior to the

next forward thrust of the needle, and while the cord is engaged by the teeth of the feed-block, the latter descending and returning to starting position while the bender forms a bend in the work, the feed-block then rising into engagement with the cord to position and support it for penetration by the needle on the next cord-penetrating thrust. 70

7. In a sewing-machine, a feed-bar movable longitudinally and also adapted to rock in a plane at right angles to the needle path, a feed-block having a concaved operative face and carried by said bar, an elevating and a feeding cam to effect, respectively and in sequence, a positive rise of said bar and the feed-block and a longitudinal movement thereof to feed, a spring arm engaging the end of the bar to lower it and the feed-block and also to effect the return stroke of said parts, said elevating cam having a dwell portion to maintain the feed-block stationary after its rise and prior to the feed stroke, stitch-forming mechanism, including a reciprocating, eye-pointed needle, a throat-plate slotted for the reception of the feed-block and provided with means to guide a cord beneath the work, and a bender to form a bend in the work prior to each alternate forward thrust of the needle, when the feed-block is depressed, said feed-block being held 80 elevated and stationary on the intervening thrusts of the needle to position the cord for penetration thereby. 90

8. In a sewing machine, a reciprocating eye-pointed needle, a longitudinally grooved throat-plate slotted in its bottom, a feed bar movable longitudinally and also up and down, a feed-block having a concaved operative face and sustained by said feed bar and occupying the slot of the throat-plate, a lever engaging said feed-bar, an elevating and a feeding cam acting on said lever and operating through the latter to first raise the feed-block thereby to place a cord in the groove in position to be penetrated by the needle, then to cause a dwell in the movement of the feed-block while a stitch is being inserted through the cord, and subsequently to move the feed-block forward, a bender to form a bend in the work in the path of the needle when the feed-block is lowered, and a resilient retractor to lower said feed-block and also to effect the return stroke thereof after its feeding movement, the positive elevation of the feed-block lifting a cord in the groove of the throat-plate and positioning it for penetration by the needle on one forward thrust, while descent of the feed-block permits the bender to bend the work in the needle path to be penetrated by the needle on its next forward thrust, the formation of a bend in the work depressing the cord below the needle path. 110 115 120 125

9. In a sewing machine, a reciprocating eye-pointed needle, a longitudinally grooved 130

throat-plate slotted in its bottom, a feed bar movable longitudinally and also up and down, a feed block having a concaved operative face and sustained by said feed bar and occupying the slot of the throat-plate, a lever engaging said feed bar, and provided with two lips, an elevating cam engaging one lip and acting through the lever to raise the feed block thereby to place a cord in the groove in position to be penetrated by the needle and then to cause a dwell in the movement of the feed block while the needle is inserted through and withdrawn from the

cord, a feeding cam acting on the other lip to give the feed block forward feeding movement after the needle is withdrawn, and a bender to form a bend in the work in the path of the needle when the feed block is lowered. 15

In testimony whereof, I have signed my name to this specification, in the presence of two subscribing witnesses.

JOHN KIEWICZ.
